BABY JUMPER

Daniel Berlin, 4424 Paul St., Philadelphia, Pa.

Filed Mar. 21, 1960, Ser. No. 59,797

Term of patent 14 years

(Cl. D15—1)

FIG. 1

FIG. 3

Fig. 1 is a front perspective view of a baby jumper, showing my design;

Fig. 2 is a rear perspective view; and

Fig. 3 is a side elevational view of the article in its collapsed or folded position.

I claim:

The ornamental design for a baby jumper, substantially as shown.
